UNITED STATES PATENT OFFICE.

CHARLES WORDEN, OF YPSILANTI, MICHIGAN.

APPARATUS FOR REGULATING THE FLOW OF WATER FROM CISTERNS.

Specification of Letters Patent No. 29,742, dated August 21, 1860.

To all whom it may concern:

Be it known that I, CHARLES WORDEN, of the city of Ypsilanti, in the county of Washington and State of Michigan, have invented 5 a new and useful Machine for Regulating the Water in and Discharging Water from Cisterns, which I call "Worden's Self-Regulating Gage and Discharge-Pipe for Cisterns;" and I do hereby declare that the following is a full, clear, and exact description 10 of the construction and operation of the same, reference being had to the annexed drawings, making a part of this specification, in which the machine is shown in perspective, the front and left-hand sides of 15 the box of the machine being removed to expose the internal structure and operation of it.

A, represents the connection of the conductor pipe as it comes from the roof and enters the machine.

B, represents an upper chamber in the machine, separated from the lower part of the partition D, which extends through the 25 whole length and breadth of the machine.

C is a circular opening in the partition D, through which the water passes on entering the machine, while the cistern is but partially full.

30 F, and G, are openings in the inner wall W, through which the water readily passes, falling through the uninclosed part of the bottom, marked H, into the cistern below.

E, is a square piston head attached to the 35 rod L, L, and moving freely up and down in the space between the partition D, and the bottom S.

J represents a rim or flange inserted in the orifice C, in the partition D, and extending 40 a small distance below. K, is the discharge pipe, into which the water may flow from the upper chamber B, and pass off where you choose.

O, R, N, are braces attached at the outer 45 ends to the bottom of the machine, and at the inner ends, to the ring P, for the better support and guidance of the piston rod L, L, that it may work more surely and easily in the machine.

50 I, is a float, run upon the rod L, L, over the screw X, and kept in place, or adjusted upon the rod, by the nut M, above the float,

and a nut on the under side of the float, not seen in the drawings.

The upper part or surface of the piston 55 head E is covered with a piece of soft sole leather, or india rubber pad.

The machine may be made of tin, copper, brass, or other sheet metal, similar to that of which the conductors on the building are 60 made, the float being the same, and soldered air and water tight, and of size sufficient to balance or excel the pressure in the discharge pipe K, and according to the height to which that pipe is to be carried up. 65

To use the machine, adjust it to the lower end of the pipe A, leading into the cistern, carefully securing and sustaining the machine to the frame work or curb over the cistern; adjust the float I, so that when the 70 water in the cistern reaches the highest point desired, the piston head E, shall be carried up by the float, and pressed firmly against the lower edge of the rim J. The discharge pipe K, is properly placed for the desired 75 drainage. The water enters the cistern through the machine, coming in at the pipe A, passing to the chamber B, then through the orifice C, upon the piston head E, and through the openings F and G and the open 80 part of the bottom marked H, into the cistern below. As the cistern fills, the water reaches the float I, which rises with the water until the piston head E, reaches, and passes firmly up against the lower edge of 85 the rim J, closing the orifice C, and filling the chamber B, until the water rises and passes off through the discharge pipe K, the cistern receiving no more, but remaining 90 filled to the desired point, only.

I do not claim the piston, nor the float as my invention, both being old devices, but

What I do claim as my invention and wish to secure by Letters Patent, is—

The combination of the float, piston and 95 box, with partitions B, and W, having openings J, G, F, and pipes A and K—the whole constructed arranged and operated in the manner and for the purpose set forth.

CHARLES WORDEN.

Signed in presence of—

D. B. GREENE,
A. WORDEN.
